UNITED STATES PATENT OFFICE.

RICHARD B. STRICKLAND, OF WACO, TEXAS.

AUTOMATIC MECHANICAL COTTON TRAMPER.

Application filed June 11, 1921. Serial No. 476,789.

To all whom it may concern:

Be it known that I, RICHARD B. STRICKLAND, a citizen of the United States, residing at Waco, in the county of McLennan and State of Texas, have invented a new and useful Automatic Mechanical Cotton Tramper, of which the following is a specification.

This invention relates to cotton tramping machines, and more particularly to a machine to be used in connection with cotton presses or the like.

The primary object of the invention is to provide an automatic mechanically operated cotton tramper wherein the length of the stroke of the tramper may be varied to efficiently accomplish the tramping result, and the power applied to the tramper by means of eccentrics and a system of levers.

A further object of the invention is to provide means for controlling the adjustment of the tramper stroke, the means being operated either while the machine is idle or while the machine is in motion.

A still further object of the invention is to provide an arrangement of levers and operating arms to insure the power being applied evenly and uniformly during the operation of the tramper, into and out of the press box.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:—

Figure 1 is a side elevational view of a machine constructed in accordance with the present invention.

Figure 2 is a plan view of the same.

Figure 3 is an end elevational view of the machine; and

Fig. 4 is a sectional view taken on line 4—4 of Figure 1.

Referring to the drawings in detail, the device comprises a base 5 to which are secured the uprights 6 that are connected at their upper ends by means of the horizontal bars 7, there being a supporting bar 8 connecting the bar 7 intermediate the ends thereof.

The uprights 6 are connected intermediate their ends by means of the horizontal bars 9, the bars 6 and 7 being arranged to provide a housing or support for the tramper and its operating rods, to be hereinafter more fully described. A pair of uprights 10 are supported adjacent to one end of the base 5 and have connection with the horizontal bars 11 at the upper ends thereof, the bars 11 being of lengths to extend through the housing where the same have connection with the uprights 6, in any suitable manner.

Connecting the bars 9 at points intermediate their ends is a supporting bar 12 which is provided with openings to accommodate the spaced guides 13 which are tubular in formation and have their upper ends disposed in the bar 8, which is mounted at the upper end of the housing.

A press box indicated at 14 is formed in the base 5 at a point directly under the bar 12 and in which operates the tramper 15 which is formed of a plurality of spaced bars 16 secured to the lower surface of the head 17.

A block indicated at 18 extends upwardly from the tramper head and provides a support for the lower sections 19 of the toggle structure or rods employed in operating the tramper.

The upper sections of the toggle are indicated at 20 and have pivotal connection with the sections 19 as through the bolts 21, which bolts also provide means for connecting the forked ends 22 of the connecting rods 23 which are operated to move the toggles.

Adjusting rods on beams 24 and 25 are supported at the upper end of the housing, each rod or beam operating through the guides 26 secured to the bars of the housing, the adjusting rods or beams being of lengths so that the ends thereof will project beyond the upper bars 7 where the rod or beam 24 has connection with the operating lever 27 which is pivotally supported by the housing as through the arm 28 and collar 29 which embraces a portion of the operating lever 27.

The upper sections of the toggle have connection with these adjusting rods or beams 24 and 25 respectively, so that movement of the rods or beams results in a relative movement of the upper sections of the toggle to shorten or lengthen the stroke of

the toggle, with the result that the stroke of the trumper is correspondingly adjusted. Connecting the adjusting rods or beams is a bar 30 which is pivotally connected to the bar 8 as by the bolt 31, one end of the bar being forked to accommodate the pin 32 carried by the adjusting rod or beam 25, there being provided a slot 33 formed adjacent to the opposite end of the bar 30 to accommodate the pin 34 of the bar 30. Thus it will be seen that movement of the adjusting rod or beam 24 in one direction results in a movement of the rod or beam 25 in the opposite direction. Coiled springs 35 have connection with the upper ends of the upper sections of the toggles, and have connection with the bars 7 of the housing to restrict movement of the adjusting rods or beams 24 and 25.

Operating in the guides 13 are the rods 36 which have their lower ends connected to the trumper and operate through the guides 13 to insure a true operation of the trumper into the presser box. Supported above the housing is a bracket 37 in which is mounted the pulley 38 over which operates the flexible member 39, the flexible member also operating over the pulley 40 supported in the bracket 41, there being provided a weight 42 as secured to the free end of the flexible member 39. The opposite end of the flexible member 39 has connection with the trumper to counterbalance the weight thereof and eliminate sudden strains being directed thereto, when the machine is running free.

The connecting rods 23 have connection with the crank arms 42' forming a part of the shaft 43 which is mounted in the bearing 44, the shaft 43 carrying a relatively large pinion 45 which is in mesh with the pinion 46 mounted on the shaft 47 and on which shaft the power pulley 48 is secured, whereby rotary movement may be imparted to the pinions 45 and 46 to accomplish the operation of the machine.

A hopper 49 forms a part of the device and this hopper is designed to receive material from a gin or the like, the material being passed from the hopper between the rollers 50, where the same falls onto the delivering board 51 which is inclined downwardly to cause the material to gravitate towards the lower end thereof, where the same falls into the presser box.

Vertical guides 52 are disposed adjacent to the ends of the delivering board 51, and provide supports for the vertically movable guard 53 which has eyes 54 embracing portions of the rod 52, to permit the same to move freely thereover. Extending laterally from the guard 53 is an arm 55 which normally lies in the path of travel of the trumper, so that when the trumper moves upwardly, the guard 53 will also be moved

upwardly permitting a quantity of cotton to pass into the presser box. A weight 56 is supported by the guard 53 so that as the trumper moves downwardly into the presser box, the guard 53 will also be moved to the limit of its downward movement to retard the movement of the cotton over the delivering board 51.

From the foregoing it will be seen that as the press box is filled, the operator may, by moving the operating lever 27 shorten the stroke of the presser or trumper, to relieve the trumper of undue strain during the tramping operation.

Having thus described the invention, what is claimed as new is:—

1. In a device of the character described, a frame, a presser box within the frame, a presser operating within the presser box, a toggle having connection with the trumper, means having connection with the toggle for controlling the same to reciprocate the trumper, and means having connection with the upper end of the toggle for moving the upper end of the toggle to adjust the stroke of the trumper.

2. In a device of the character described, a frame, a presser box within the frame, tubular guides within the frame, a trumper supported by the frame, guide rods operating through the tubular guides and having connection with the trumper for guiding the trumper in its movement, toggles having connection with the trumper for reciprocating the trumper, and means for adjusting the stroke of the trumper.

3. In a device of the character described, a frame, a presser box within the frame, a trumper operating within the presser box, a toggle having connection with the trumper, horizontally disposed adjusting rods supported at the upper end of the frame and having connection with the upper end of the toggle, means for moving the adjusting rods to vary the stroke of the trumper, and means for delivering material to the presser box.

4. In a device of the character described, a frame, a presser box within the frame, a trumper operating in the presser box, means for reciprocating the trumper, means for delivering material to the presser box, and means for adjusting the stroke of the trumper while the same is in motion.

5. In a device of the character described, a frame, a presser box within the frame, a vertically movable trumper operating in the frame, adjusting rods disposed at the upper end of the frame, a toggle having connection with the adjusting rods and trumper, a pivoted bar connecting the rods, an operating lever having connection with one rod whereby movement of one rod produces a relative movement of the other rod to adjust the stroke of the presser, means for returning

the adjusting rods to their normal positions, and means for delivering material to the presser box.

6. In a device of the character described, 5 a frame, a presser box within the frame, a trumper operating within the frame, means for imparting movement to the trumper, adjusting rods, means connecting the adjusting rods and trumper for adjusting the 10 stroke of the trumper, means for moving the adjusting rods in one direction, and automatic means for returning the adjusting rods to their normal positions.

7. In a device of the character described, 15 a frame, a presser box within the frame, a trumper operating in the frame, adjusting rods supported at the upper end of the frame, means connecting the adjusting rods and trumper whereby movement of the adjusting rods will vary the stroke of the 20 presser, means for delivering material to the presser box, means for adjusting the adjusting rod, and spring means for returning the adjusting rods to their normal 25 positions.

8. In a device of the character described, a frame, a presser box within the frame, a vertically reciprocating trumper supported

within the frame, means for reciprocating the trumper, means for adjusting the stroke 30 of the trumper, trumper controlled means for delivering material to the presser box, and means for counterbalancing the weight of the trumper when the device is running idle.

35

9. In a device of the character described, a frame, a presser box within the frame, a trumper operating in the presser box, means for reciprocating the trumper, guide rods disposed laterally of the presser box, a reciprocating guard operating over the guide rods, an arm carried by the guard and lying within the path of travel of the trumper, said trumper adapted to contact with the arm for moving the guard vertically to control the passage of material to the presser box, and means for delivering material to the guard.
